UNITED STATES PATENT OFFICE

BURGESS G. HODGES, OF BOSTON, MASSACHUSETTS

MAN'S NECKWEAR

Application filed May 31, 1930. Serial No. 457,868.

This invention relates to men's neckwear, and pertains more particularly to improvements in bow ties of the made-up type in which the tie is shaped and arranged for wear before it is applied to the wearer's neck. A principal object of the invention is to provide a simple and inexpensive yet durable and attractive tie of the aforesaid type, in which the bow element may be rearranged at the pleasure of the wearer selectively to display any one of two or more, preferably four, fabric faces at the front of the tie, and in which said bow element is securely affixed in its desired position against accidental displacement or distortion.

Further objects are to provide a tie having a pair of reversible bow members, as above indicated, and a central loop or strap member which is also reversible and which is detachably fastened about the bow members; to provide fastening means passing through the throats of the bow members and preferably also through the ends of the retaining loop, to secure said members against relative displacement; to provide simple means for connecting the assembled tie to a neckband of common form, and in general to improve the construction of bow ties of this class and to produce a tie which has unusually long life, which always looks clean and neat, and which is easily and quickly rearranged when necessary and applied or removed from the neck of the wearer.

Recommended embodiments of my invention are illustrated in the accompanying drawings in which:

Fig. 1 is a front view of the assembled bow;
Fig. 2 is a rear view thereof;

Fig. 3 is a face view to smaller scale of a form of separable bow member which may be employed in forming the improved bow;

Fig. 4 is a face view of the retaining loop;

Fig. 5 is an edge view of a pair of superposed bow members such as shown in Fig. 3, illustrating the manner in which the encircling band is applied thereto;

Fig. 6 is a view similar to Fig. 5 showing the band in attached position;

Fig. 7 is a face view of an optional form

of bow element which may be used in making up the tie of Figs. 1 and 2;

Fig. 8 is a composite view of a recommended form of fastening means; and

Fig. 9 is a composite view of a modified form of fastening.

The bow element shown in the particular embodiment of the invention chosen for the purpose of illustration in Figs. 1 to 6 inclusive, comprises a pair of separable members 60 11 and 12, each preferably having a filler 13 of flexible reinforcing material such as treated paper or the like and a fabric covering of silk or other appropriate material in plain colors or of any desired ornamentation or design. The silk covering of each member preferably consists of a single piece of material folded lengthwise over the opposite ends of the reinforcing sheet 13 and stitched as at 65 14 (Fig. 3) at the center or throat portion of the bow, the longitudinal margins of the covering material having seams extending along the upper and lower edges of the reinforcement, as indicated at 15 (Figs. 5 and 6). It is thus apparent that the wings of the bow members present front and back surfaces of the same external appearance, so that either face of either member may selectively be employed at the front of the bow; and it is also 70 obvious that the four display faces thus provided may be of different color or pattern if desired.

The throat portions 16 of the bow members 11 and 12 have central apertures preferably reinforced by eyelets 17. A retaining loop 85 or strap 18 having a silk covering which may be of the same material as the bow covering, and which is also preferably reversible, is arranged to encircle the throat portions 16 of the superposed bow members 11 and 12. One end of this loop preferably has an eyeleted opening 19 and an elastic strip 20 may be secured transversely at the opposite end of the band by an eyelet 21.

In a modified form of my tie, I may employ 95 a bow element such as illustrated in Fig. 7, which shows a series of connected or integral bow members constituting a continuous strip so that the strip may be folded into thirds on the broken lines 22 with either face of either 100

of the end bows 23 or 24 presented at the front. The throat portions 25 of the three bow members are thus brought into superposed juxtaposition, and said portions preferably have eyeleted openings 26 registering with each other when the bow members are thus superposed. This optional form of bow element is arranged and mounted substantially in the same manner as the bow element comprising the separable members 11 and 12, as now to be described; but it is obvious the folded strip of Fig. 7 provides a three-ply bow with folds at its opposite ends, instead of the double thickness, free-edged arrangement shown in Figs. 5 and 6.

The superposed bow members are preferably connected together by suitable fastening means passing through the eyeleted openings at their throat portions and through the eyelets 19 and 21 of the loop 18. The fastening means may comprise a staple fastener 27 (Fig. 8) which is passed through said openings and has its prongs bent outwardly over a slotted washer 28. Fig. 9 shows another optional form of fastening comprising a socket member 29 and a screw 30 threading therein. It is apparent that other forms of separable or other fasteners may be employed for attaching the central portions of the bow members to the retaining loop, thereby to prevent relative displacement of said elements.

In assembling the parts of the bow, the bow makers are superposed and the fastening element is passed through the registering openings thereof from the front of the bow; the eyelet at one end of the loop 18, for example the eyelet 19, is then slipped over the prongs of the fastener 27 (in case a staple fastener is used); the opposite end of the loop with its transverse strip 20 is passed around the throat portions of the bow members and over the head of the fastener, and its eyeleted opening 21 is received upon the fastener prongs, as indicated in Figs. 5 and 6. The several elements of the bow are thus quickly and easily assembled and secured in proper relation, the head of the fastener 27 being concealed by the front portion of the reversible loop 18. In case the fastener of Fig. 9 is used, it will be apparent that the part 29 is inserted through the openings in the bow members, the loop 18 is turned around the bows, and the screw 30 is then fitted through the registering loop openings and into the socket 29.

The elastic band 20 may have rings 31 at its opposite ends, so that the assembled bow may be held in position by a neck band 32 of common construction having end hooks 33 detachably engaging respective rings. Other suitable securing means may be employed, however, to support the bow in proper position.

It is thus apparent that I have provided a

made-up bow which is simple and economical to manufacture, easy to assemble and rearrange in the desired manner, attractive in appearance, and extremely durable in use owing to the exchangeability of its bow members and the reversibility of the throat loop. In case the exposed face of the outer bow member should become soiled, the user may readily detach the fastening means and either reverse the position of said member or interchange the front and back members, in order to present a fresh and clean surface to view. It is obvious that the constructions above described permit any one of the four sides of the bow members to be selectively and successively exposed at the front of the bow; and that the throat loop, which is less likely to be wrinkled or soiled, has two similar sides which may be alternatively turned outwardly. The life of the improved bow tie is consequently prolonged far beyond the useful life of an ordinary made-up bow; and a pleasing appearance at all time is ensured.

While a tie constructed as herein illustrated and described is particularly adapted to satisfy the purposes of this invention, it will be understood that details of structure and arrangement may be varied to suit particular purposes without departing from the spirit of my invention as defined in the following claims.

I claim:

1. A bow tie comprising bow members arranged in superposed relation with either side of either member selectively disposed at the front of the tie, the central portions of said members having eyeleted openings, fastening means passing through said openings, and a loop member surrounding said central portions having openings at its joined ends receiving said fastening means, so that said members are secured against relative displacement, the loop member having eyes for receiving the hooks of a neckband for holding the tie in position.

2. A bow tie comprising a pair of separable bow members each having opposite sides of the same general external contour and appearance, so that either side of either member may be selectively exposed at the front of the tie when the two members are superposed, each member having a throat portion, a removable and reversible loop member encircling said throat portions and having its ends overlapping at the back of the tie, and means extending through said throat portions and through the overlapped ends of the loop for retaining said members in assembled relation, the loop having laterally extending band portions provided with eyes for receiving the fastenings of a neck band for holding the tie in position.

Signed by me at Boston, Massachusetts, this 26th day of May, 1930.

BURGESS G. HODGES.
